UNITED STATES PATENT OFFICE

161,895

OPEN-TOP REFRIGERATED SELF-SERVE
CASE

George K. Bently, Kendallville, Ind., assignor to McCray Refrigerator Company, Kendallville,
Ind., a corporation of Indiana

Application July 27, 1950, Serial No. 11,428

Term of patent 7 years

(Cl. D80—9)

To all whom it may concern:

Be it known that I, George K. Bently, a citizen of the United States, and resident of Kendallville, in the county of Noble and State of Indiana, have invented a new, original, and ornamental Design for an Open-Top Refrigerated Self-Serve Case, of which the following is a specification, reference being had to the accompanying drawing, forming a part thereof.

In the drawing, Fig. 1 is a perspective front view of an open-top refrigerated self-serve case showing my new design; Fig. 2 is a front view thereof, and Fig. 3 an end view, both ends having the same appearance.

The rear of the instant article is substantially plain. The dominant features of my new design are shown in full lines.

I claim:

The ornamental design for an open-top refrigerated self-serve case, substantially as shown and described.

GEORGE K. BENTLY.
